Primary Examiner — Nathan M Johnston(74) *Attorney, Agent, or Firm* — 3M Innovative Properties Company; Trisha D. Adamson(57) **CLAIM**

The ornamental design for a tube securement device, as shown and described.

DESCRIPTION

FIG. 1 is a perspective view showing the new design for a tube securement device;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The surface shading illustrated in the drawings is provided merely to highlight the contour of design; it is not intended to be illustrative of texture or gloss.

The broken lines in the drawings represent perforated lines within the tube securement device front and rear surface and form part of the claimed design.
